UNITED STATES PATENT OFFICE.

HENRY H. LAMPERT, OF CHICAGO, ILLINOIS.

CLIP FOR REINFORCING-BARS.

1,126,493.

Specification of Letters Patent. Patented Jan. 26, 1915.

Application filed October 22, 1913. Serial No. 796,590.

To all whom it may concern:

Be it known that I, HENRY H. LAMPERT, a citizen of the United States of America, and a resident of Chicago, county of Cook, 5 and State of Illinois, have invented certain new and useful Improvements in Clips for Reinforcing-Bars; of which the following is a specification.

The main objects of this invention are to 10 provide an improved wire clip for securely tying together at their intersections the reinforcing bars of concrete structures, and which is also adapted to space the bars away from the mold walls whether the bars are 15 disposed horizontally or vertically; to provide a wire clip which may be applied quickly and easily to the reinforcing bars; to provide a clip which may be bent to final form before application to the bars and 20 therefore not required to be bent or shaped by the workmen applying them; and to provide a clip formed from a single piece of wire and serving equally as well to tie together bars which are disposed diagonally 25 to each other, or those disposed at right angles to each other.

An illustrative embodiment of this invention is shown in the accompanying drawings, in which—

30 Figure 1 is a perspective view of the improved clip as applied to a pair of intersecting reinforcing bars. Fig. 2 is a plan view. Fig. 3 is a plan view of a clip as it appears when applied to diagonally intersecting bars. Fig. 4 is a perspective view of a modified form of the clip applied to a pair of intersecting bars.

The completed clip before it is applied to 35 reinforcing bars is of the form shown in Fig. 1 with its locking arm 10 disposed as shown by dotted lines in this view. The clips are formed of single pieces of wire 1 bent into the form to provide the loop 2 and the arms 3 and 4. The arm 4 is considerably longer than the arm 3, and each of the 40 arms is bent upon itself to form the feet 5 and 6, and the free ends 7 and 8. The feet 5 and 6 are preferably twisted as shown so that they are better adapted without bending 45 to support the weight of the reinforcing bars. The loop 2 is bent away from the feet 5 and 6, and again at about midway between the feet 5 and 6, and its end is bent upwardly at 11. The end of arm 3 is 50 slightly curved as designated by the numeral 12, and the arm 4 is bent at the point

13 to extend toward the loop 2, and also has its end 14 bent or curved.

When the clip is applied to a pair of reinforcing bars 15 and 16 the arms of loop 2 50 pass from the legs 5 and 6 around the under side of bar 16 over the upper bar 15. The curved end 12 of arm 7 grips the upper side of bar 15 at about the location at one side of bar 16 that loop 2 is at the other side. 65 The curved end 14 of the arm 8 engages the under side of bar 15 at a point beyond the loop 2. The clip being made of resilient material, the locking arm 8 is normally urged to return to the position indicated by 70 dotted lines, but as this movement is prevented by the reinforcing bar 15 the action will cause the clip to firmly engage the bar 16 at points 11, and to engage the bar 15 at the curve in loop 2, and the end of arm 7. 75 The bars are by this means firmly tied together.

In applying the clip to the intersection of a pair of reinforcing bars, referring to Fig. 2, its ends 12 and 14 are passed downwardly 80 at each side of bar 15 to the right of bar 16 and then caused to pass upwardly at each side of bar 15 to the left of bar 16, coming to the position indicated in Fig. 1 with arm 10 extending upwardly as indicated by the 85 dotted lines. In this position the clip is fairly loose and free to move on the reinforcing bars, but by springing the arm 10 around the bar 15 so that its curved end 14 90 engages the under side of the bar, the clip becomes tightly engaged with both of the reinforcing bars and securely ties the same together. The end of arm 7 may be left straight as indicated by the dotted lines in Fig. 1, or curved as shown by the full lines. 95 When the arm 7 is left straight the clip is still effective to firmly tie together the two bars, as the application of its spring pressure occurs below bar 16 at the point 11, and above and below the bar 15 at the loop 2 and the curved end 14. The loop 2 prevents rod 15 from moving around rod 16 in one direction, while the curved end 14 prevents it from moving around the rod 16 in the other direction. 100

Fig. 3 shows the clip suitably bent at the loop 2 to adapt the clip for use in tying together bars which diagonally cross each other. In other respects the clip is the same as shown in Fig. 1.

The modification shown in Fig. 4 differs from the clip shown in the remaining fig-

ures in that the loop 2 is not offset from the legs 5 and 6, and the legs are not twisted, and also the curved ends of arms 7 and 8 are arranged to both engage the upper side 5 of bar 15 on the opposite side of bar 16, to that of the loop 2. The modified clip is applied to reinforcing bars much in the same manner as the clip above described; that is, its arms 7 and 8 are passed down- 10 wardly around each side of bar 15, and then underneath bar 16, and finally have their curved ends snapped over the upper side of bar 15. The spring pressure in the clip in this case results in bearing downwardly on 15 bar 15 at the loop 2 on one side of bar 16, and at the curved ends 18 on the other side of the bar 16, while the bar 16 is forced upwardly into contact with bar 15 at the points 19 of arms 7 and 8.

20 It will be understood that numerous details of the constructions shown may be altered or omitted without departing from the spirit of this invention as defined by the following claims.

I claim:—

1. A wire clip of the class described, comprising a single piece of wire bent into a U shape with the arms of the U bent backward upon themselves, and the loop of the U being bent outwardly from said arms, one of said arms being provided with a bent locking end. 25
30

2. A wire clip of the class described, comprising a piece of wire bent into U-shape with the arms of the U bent backward upon themselves, forming supporting legs, the free ends of the arms and the U-portion being bent with relation to each other to form a seat for a reinforcing bar, the ends of said arms being provided with a bent portion 35 for engagement with a reinforcing bar. 40

Signed at Chicago this 20th day of October, 1913.

HENRY H. LAMPERT.
